UNITED STATES PATENT OFFICE.

CRAYTON E. WOMER, OF REPUBLIC, OHIO.

RAILWAY-TIE.

No. 896,501.

Specification of Letters Patent. Patented Aug. 18, 1908.

Application filed September 26, 1907. Serial No. 394,734.

To all whom it may concern:

Be it known that I, CRAYTON E. WOMER, a citizen of the United States, residing at Republic, in the county of Seneca and State of 5 Ohio, have invented a new and useful Railway-Tie, of which the following is a specification.

This invention relates to railway ties and its object is to provide a metallic tie which is 10 of simple and durable construction and which is provided with means whereby rails can be securely fastened thereto.

A still further object is to provide cushioning means by the use of which the noise and 15 vibration produced by trains passing over the rails can be reduced to the minimum.

Another object is to provide a tie formed of few parts and which can be conveniently stored in a small compass before the parts are 20 assembled.

With these and other objects in view the invention consists of certain novel features of construction and combinations of parts which will be hereinafter more fully described and 25 pointed out in the claims.

In the accompanying drawings is shown the preferred form of the invention.

In said drawings: Figure 1 is an end elevation of a tie embodying the present improvements, a rail being shown in position thereon. 30 Fig. 2 is a section through one end portion of the tie, said section being taken on the line $x-x$, Fig. 1. Fig. 3 is a detail view of one of the supporting blocks of the tie.

Referring to the figures by characters of reference, 1 designates a base plate on which is mounted a metal supporting block 2 preferably rectangular in form and having laterally extending flanges 3 at the bottom thereof 40 each of which is formed with an upstanding guard rib 4 spaced from the adjoining side of the block 2 a distance equal to the thickness of the tie body. This tie body which has been indicated by the numeral 5 is preferably 45 formed of a length of sheet metal having its side portions perpendicular to its intermediate portion so that said body portion is substantially U-shaped. The same is so proportioned as to fit snugly at each end upon a 50 supporting block such as described and with its edges lapped by the guard ribs 4 as indicated in Fig. 1. Registering openings 6 and 7 are formed within the block 2 and the base plate 1 respectively and are designed to receive a U-shaped securing rod 8 the end portions of which extend through openings 9

formed within the body portion 5 and register with the opening 6. These end portions also project through a cushion 10 preferably formed of rubber and which rests upon the 60 body portion 5 directly above the block 2 and constitutes a support for a chair 11. This chair is preferably formed of sheet metal and has guard flanges 12 along the side edges thereof designed to retain rail engaging blocks 65 13. These blocks are so shaped as to fit upon the base flanges 14 of a rail 15 and both the blocks 13 and the chair 11 have openings through which the end portions of the rod 8 project. The extremities of this rod are 70 screw threaded as indicated at 16 and are designed to be engaged by nuts 17. Obviously by tightening these nuts all of the parts of the tie can be securely bound together and the rail will at the same time be held tightly 75 in place upon the chair 11 by means of blocks 13. It will thus be seen that a single securing member serves both to fasten the rail in position and to hold the parts of the tie together. 80

Importance is attached to the provision of the cushion 10 which, as before stated, is preferably formed of rubber. This cushion will serve as an effective means for preventing noise and vibration such as produced 85 when cars are traveling over the rails and it can also constitute a partial means for insulating the two rails of a track and is therefore advantageous for use in connection with electric railroad systems or in connection with 90 railways in which the rails are used as conductors for electrical signaling apparatus and the like. Although only one supporting block 2, cushion 10, etc. have been shown in the drawings it is to be understood of course 95 that these parts are to be arranged at both ends of the body 5 to form a complete tie so that each of the rails will be supported and cushioned in the same manner. The base plate 1 is designed to be covered by ballast 100 so as to constitute an anchor and the ballast can also extend upward into the body 5 between the blocks 2 and it is obvious that by arranging the ballast in this manner the tie will be positively prevented from creeping. 105

It is to be understood that, if desired, the cushions 10 may be dispensed with. It is also to be understood that if desired the base plates 1 may be dispensed with, in which event the blocks 2 will serve to anchor the tie 110 and hold it against creeping. Importance is attached to the fact that the intermediate

portion of the channel or trough-like body 5 of the tie is uppermost and does not rest upon the roadbed. The danger of the tie splitting along the sides of the intermediate portion is thus eliminated. It will be seen that a rail can be readily removed at any time simply by removing the fastener 13.

What is claimed is:

1. The combination with an inverted channeled body portion; of a base plate, a supporting block thereon and within the body portion, and means extending through the plate, block and body portion for binding said parts together, said plate extending beyond the block and constituting an anchor.
2. The combination with an inverted channeled body portion, a cushion thereon, a chair upon the cushion, and rail engaging means within the chair; of a supporting block within the body, and means for binding together the block, the rail engaging devices, and the parts interposed therebetween.
3. The combination with a supporting block; of an inverted channeled body upon and embracing the block, means upon the block for engaging and retaining the edge portions of the body, and means for securing the body and block together.
4. The combination with an inverted channeled body; of a supporting block therein, means integral with the block for engaging and retaining the edge portions of the body, an anchoring plate extending under and beyond the block, and means for securing the body, plate and block together.
5. The combination with an inverted channeled body; of a supporting block thereon and within the body portion, and means extending through the plate, block and body portion for binding said parts together, said plate extending beyond the block and constituting an anchor.

neled body; of a supporting block therein, means integral with the block for engaging and retaining the edge portions of the body, an anchoring plate extending under and beyond the block, means for securing the body, plate and block together, and rail engaging devices above the body and secured by said means.

6. The combination with a body, a supporting block thereunder, a substantially U-shaped securing device extending through the block and body; of a chair engaged by said securing device and having integral guard devices, a cushion interposed between the body and chair, and rail engaging devices upon and engaged by the respective end portions of the securing device.

7. The combination with a body, a supporting block thereunder, an anchoring device beneath and extending beyond the block, and a substantially U-shaped securing device extending through the plate, block and body; of a chair engaged by said device and having integral guard flanges, a cushion interposed between the chair and body, and oppositely disposed rail engaging devices upon the chair and engaged by the respective ends of the securing device.

In testimony that I claim the foregoing as my own, I have hereto affixed my signature in the presence of two witnesses.

CRAYTON E. WOMER.
